CIRCUIT INTERRUPTER

Gilbert J. Easley, Forest Hills, Pa., assignor to
Westinghouse Electric Corporation, East Pittsburgh, Pa., a corporation of Pennsylvania

Application October 30, 1946, Serial No. 706,733

10 Claims. (Cl. 200—150)

1

This invention relates to circuit interrupters, in general, and more particularly to arc-extinguishing structures therefor.

A general object of my invention is to provide an improved circuit interrupter of the type drawing both a pressure-generating arc and an interrupting arc in which contact parting is more quickly attained to obtain a high speed type of interrupter.

A more specific object of my invention is to provide an improved circuit interrupter of the foregoing type in which a substantially enclosed dashpot is associated with the intermediate contact to obtain practically simultaneous contact parting without the additional complication and expense of including a side operating rod.

This invention is an improvement over that disclosed in U. S. Patent application, Serial No. 465,244, filed November 11, 1942, now U. S. Patent 2,406,469, issued August 27, 1946, by Leon R. Ludwig, Winthrop M. Leeds, and Benjamin P. Baker, and assigned to the assignee of the instant application, and in which there is disclosed and claimed a high speed type of circuit interrupter in which a pivotally mounted pressure-generating contact is moved by a side operating rod relative to a stationary intermediate contact to establish a pressure-generating arc simultaneously with movement of a lower movable contact from the intermediate contact to draw the interrupting arc.

Such a construction, aside from the complication of a side operating rod, is high speed in action since both the pressure and interrupting arc are simultaneously drawn away from the intermediate contact the requisite arc length.

It is a further object of my invention to obtain the advantages of simultaneous break operation obtained in the interrupter described in the Ludwig et al. patent, while at the same time avoiding the necessity of utilizing the side operating rod for actuating the pressure-generating contact.

Further objects and advantages will readily become apparent upon a reading of the following specification taken in conjunction with the drawings, in which:

Figure 1 is a side elevational view, partly in section, of a circuit interrupter embodying my invention and shown in the closed circuit position;

Fig. 2 is an enlarged vertical sectional view, with a portion taken at a quarter section, as shown by the lines II—II of Fig. 3, of the left-hand arc-extinguishing unit of Fig. 1, the con-

tacts being shown in the partly open circuit position; and

Fig. 3 is a sectional view taken substantially along the line III—III of Fig. 2 looking in the direction of the arrows.

Referring to the drawings and more particularly to Fig. 1 thereof, the reference numeral 1 designates a tank in which is disposed a suitable arc-extinguishing fluid 2, in this instance circuit breaker oil, filling the tank 1 to the level 3. Depending from the cover 4 of the tank 1 are two insulating bushings 5, 6 at the lower ends of which are secured rigidly in place identical arc-extinguishing units, generally designated by the reference numeral 7.

The arc-extinguishing units 7 are electrically bridged in the closed circuit position, as shown by the full lines in Fig. 1 by a U-shaped conducting cross-bar 8 reciprocally operated in a vertical direction, as viewed in Fig. 1, by an insulating operating rod 9 actuated by suitable mechanism, not shown.

Referring more specifically to Fig. 2, which shows enlarged the left-hand arc-extinguishing unit 7 of Fig. 1, it will be observed that the terminal stud 10 extending through the left-hand bushing 5 has threadedly secured and clamped to its lower end a top dome casting 11. Positioned within the top dome casting 11 is a pivotally mounted pressure-generating contact 12 biased downwardly by a compression spring 13, the latter having its upper seat against an off-standing bracket 14, in this instance forming an integral part of a plate 14a secured by bolts 14b to the casting 11. A flexible conductor 15 electrically connects the pressure-generating contact 12 to the bracket 14 and hence to the dome casting 11 so that the pivot pin 16 does not need to carry the breaker current in the closed circuit position thereof.

Preferably, an over-pressure relief valve 17 is provided to permit the relief of excessive pressure formed within the pressure-generating chamber, generally designated by the reference numeral 18 and defined by the wall portions of the dome casting 11. Also, a gas relief valve 19 is provided which closes during the interrupting operation and opens following the completion of the interrupting operation to permit accumulated gas to pass upwardly out of the pressure-generating chamber 18 and hence out of the arc-extinguishing unit 7.

Secured to the lower end of the dome casting 11 by insulating tie rods 20 are a plurality of suitably configured insulating plates forming fluid flow

passages of the type set forth in the aforesaid Patent 2,406,469. The passage structure is fully set forth in the aforesaid patent to which reference may be had for the configuration of the several plates. For the purpose of understanding my invention, it is merely necessary to note that the insulating plates collectively align to form two vertical flow passages, generally designated by the reference numeral 21, and more clearly shown by the sectional view of Fig. 3. The two vertical flow passages 21 permit communication between the pressure-generating chamber 18 and the interrupting chamber, generally designated by the reference numeral 22. The lower ends of the two vertical flow passages 21 have communicating therewith pairs of inlet passages 23 which permit fluid under pressure from the pressure-generating arc to flow to radially inwardly toward the interrupting arc 24 established between the intermediate contact 25 and the lower movable contact 26, which forms the upstanding portion of the cross-bar 8. The pressure-generating arc 27 is established between the pressure-generating contact 12 and the upper portion of the intermediate contact 25.

The oil under pressure formed by the establishment of the pressure-generating arc 27 flows downwardly, as indicated by the arrows and radially inwardly through the inlet passages 23 toward the interrupting arc 24 to pass through orifices 28 and outwardly from the arc-extinguishing unit 7 through a plurality of venting passages 29. The venting passages 29 pass out of the unit 7 in opposite directions in a direction perpendicular to the plane of the drawing of Fig. 2 and are shown more clearly in Fig. 3.

A substantially enclosed dashpot, generally designated by the reference numeral 30, is associated with the intermediate contact 25 and in this instance includes an insulating operating cylinder 31 having a vertically extending groove or grooves 32 constituting bypassing means provided therein and in which is guided in a vertical reciprocating manner a metallic ring or piston 33 secured by a screw 34, so as to move with the intermediate contact 25. A compression spring 35 has its lower seat against the piston 33 and its upper seat against an insulating plate 36 having an aperture 37 formed therein which closely surrounds the upper portion of the intermediate contact 25.

Preferably, the region 38 below the flange or ring 33 communicates with the region exterior of the arc-extinguishing unit 7 by means of a fibre tube 39 having an adjusting screw 40 at its outer end which acts as a valve to vary the size of the exhaust passage through the tube. One may cause the removal of the screw 34 from the ring 33 and intermediate contact 25 by inserting the end of a screw-driver through the fibre tube 39. When the screw 34 is removed from the ring 33 and also the intermediate contact 25, the intermediate contact 25 may be removed vertically upwardly or downwardly for repair or replacement. Since there is relatively little wear on the flange 33, there is no need for the latter's replacement.

The operation of the interrupter will now be explained. In the closed circuit position of the interrupter, as shown by the full lines in Fig. 1, the electrical circuit therethrough includes terminal stud 10, top dome casting 11, bracket 14, flexible conductor 15, rotatable pressure-generating contact 12, intermediate contact 25, lower movable contact 26 through the cross-bar 8 and through the right-hand arc-extinguishing unit in an identical manner to the other terminal of the

interrupter. To effect the opening operation of the interrupter, suitable mechanism, not shown, but which is responsive to manual operation or to overload currents carried by the interrupter causes downward movement of the insulating operating rod 9. The downward movement of the operating rod 9 causes downward movement of both lower movable contacts 26.

Because of the provision of the compression springs 13, 35 the three contacts, 12, 25 and 26 will initially move downwardly together making contacting engagement. However, the pressure-generating contact 12 will, after a predetermined clockwise rotation, strike the stop screw 12a and be halted thereby. Further downward travel of the contacts 25 and 26 will cause the establishment of a pressure-generating arc 27 within the pressure-generating chamber 18, the provision of the bypassing means 32 permitting the intermediate contact 25 to maintain contacting engagement with lower contact 26 during this time.

The downward movement of the intermediate contact 25 and the lower movable contact 26 continues with the two making contacting engagement until the flange or ring 33 secured to the intermediate contact 25 passes the lower ends of the grooves 32 provided in the insulating guide cylinder 31. When this occurs, the dashpot 30 will be effective to cause halting downward movement of the intermediate contact 25 to thereby cause a separation to take place between the intermediate contact 25 and the lower movable contact 26 to establish an interrupting arc 24 within the interrupting chamber 22 of the unit 7.

It will consequently be noted that when the flange 33 passes the lower ends of the groove 32, the dashpot 30 will thereafter cause the intermediate contact 25 to move downwardly at a slower speed than the speed of the lower movable contact 26. This draws the interrupting arc 24 in the interrupting chamber 22 which will be extinguished by the fluid flow from the pressure-generating arc 27. It will be observed that following the time of effective operation of the dashpot 30, that is, when the by-passing means becomes ineffective, thereafter both the pressure-generating and interrupting arcs 27, 24 continue to lengthen to the requisite arc length in a manner simulating that of the aforesaid Patent 2,406,469.

It will be noted that a distinct advantage of my invention is the substantially enclosed construction of the dashpot 30. Thus, pressure within the pressure-generating chamber 18 is not permitted to act upon the top or rear side of the piston 33, as it moves downwardly during its opening stroke. If there were communication between the top or rear side of the piston 33 and the pressure-generating chamber 18, during the interruption of high values of current, the separation between the intermediate contact 25 and the lower movable contact 26 would be delayed inasmuch as the pressure would assist the compression spring 35 in driving the piston 33 and intermediate contact 25 downwardly more rapidly than would be the case in interrupting low values of current. However, during the interruption of high values of current the length of the pressure-generating arc need not be so long as during the interruption of low values of current. Consequently, it is not desirable to delay opening of the interrupting contacts during the interruption of high values of current which would result should there be communication between the rear side of the piston 33 and the pressure-

generating chamber 18. Also the downward speed of the intermediate contact is substantially independent of the pressure acting on the upper end of the intermediate contact for two reasons: 1st, the pressure on the upper end is partly counterbalanced by the pressure on the lower end of the intermediate contact; 2d, it is characteristic of dashpot action, with fluid bleeding out of an orifice of fixed size, to have a rate of fluid escapement substantially independent of driving force on the piston.

It will be also observed that the adjustment of the fluid adjusting screw 40 will determine the rate of escape of oil from the region 38 in front of the piston 33 during its opening movement. Thus, the downward speed of the intermediate contact 25, as it moves within the operating cylinder 31, may be regulated. Also, the by-pass means 32 permits the dashpot 30 to be ineffective during the initial portion of the downward travel of the intermediate contact 25 and piston 33.

The further advantage results from my invention that the number of operating parts is reduced as compared with a construction involving a side operating rod as set forth in the aforesaid Patent 2,406,469. Thus, by the arrangement which I have provided, the number of operative parts is practically the same as the case where one has a two-break type of interrupter, the breaks occurring sequentially. Although strictly speaking the two breaks in my improved interrupter occur in a sequential manner, the provision of the dashpot causes the two breaks to occur almost simultaneously, and more rapidly than the ordinary sequential break type of interrupter. Also, the insulation conditions are not impaired by the utilization of my invention since no metallic parts parallel any of the arc gaps.

From the foregoing description, it will be apparent that I have provided an improved circuit interrupter of the two-break type in which by the use of my invention the breaks occur practically simultaneously. Also, it will be noted that in the operation of my invention, the interrupting arc 24 is drawn earlier than in the conventional "consecutive part" arrangement. This results by virtue of the by-passing means 32 which equalizes the pressure on both sides of the piston 33 to render the dashpot 30 ineffective during the initial portion of the opening stroke.

During the closing stroke, the movable contact 28 moves upwardly to pick up the intermediate contact 25 and raise the latter charging the compression spring 35 until the intermediate contact 25 makes engagement with the relatively stationary pressure-generating contact 12, the compression spring 13 providing the requisite contact pressure.

Although I have shown and described a specific structure, it is to be clearly understood that the same was merely for the purpose of illustration and that changes and modifications may readily be made therein by those skilled in the art without departing from the spirit and scope of the appended claims.

I claim as my invention:

1. In a circuit interrupter, a relatively stationary contact, an intermediate contact cooperable with the relatively stationary contact to establish an arc, a movable contact separable from the intermediate contact to establish a second serially related arc, a piston secured to and movable with the intermediate contact, an operating cylinder within which the piston moves, by-pass-

ing means associated with the operating cylinder to equalize the pressure on both sides of the piston only during the initial portion of the opening travel of the piston, and means preventing the arcing pressure from acting upon the piston to accelerate its opening movement.

5. In a circuit interrupter, a relatively stationary contact, an intermediate contact cooperable with the relatively stationary contact to establish a pressure-generating arc, an enclosed dashpot protected from the arcing pressure associated with the intermediate contact to delay the opening movement of the latter, a movable contact separable from the intermediate contact to establish an interrupting arc, and means rendering the dashpot ineffective during the initial portion of the opening operation.

2. In a circuit interrupter, a relatively stationary contact, an intermediate contact cooperable with the relatively stationary contact to establish an arc, a movable contact separable from the intermediate contact to establish a second serially related arc, a piston secured to and movable with the intermediate contact, an operating cylinder within which the piston and at least a portion of the intermediate contact move, a longitudinally extending groove disposed on the inner wall of the operating cylinder to equalize the pressure on both sides of the piston only during the initial portion of the opening travel of the piston, and means preventing the arcing pressure from acting upon the piston to accelerate its opening movement.

3. In a circuit interrupter, a relatively stationary contact, an intermediate contact cooperable with the relatively stationary contact to establish an arc, a movable contact separable from the intermediate contact to establish a second serially related arc, a piston secured to and movable with the intermediate contact, an operating cylinder within which the piston moves, a longitudinally extending groove disposed on the inner wall of the operating cylinder to equalize the pressure on both sides of the piston only during the initial portion of the opening travel of the piston, and means preventing the arcing pressure from acting upon the piston to accelerate its opening movement.

4. In a circuit interrupter, a relatively stationary contact, an intermediate contact cooperable with the relatively stationary contact to establish an arc, a movable contact separable from the intermediate contact to establish a second serially related arc, a piston secured to and movable with the intermediate contact, an operating cylinder within which the piston moves, a longitudinally extending groove disposed on the inner wall of the operating cylinder to equalize the pressure on both sides of the piston only during the initial portion of the opening travel of the piston, and means biasing the piston and intermediate contact in the opening direction, and means preventing the arcing pressure from acting upon the piston to accelerate its opening movement.

5. In a circuit interrupter of the liquid break type, a pair of contacts separable to establish an arc, a third contact separable from one of the aforesaid pair of contacts to establish a second serially related arc, means biasing the said one contact in the opening direction, and substantially enclosed dashpot means operative substantially independently of the arcing pressure for controlling the opening movement of the said one contact.

6. In a circuit interrupter, a relatively stationary contact, an intermediate contact cooperable with the relatively stationary contact to establish an arc, a movable contact separable from the intermediate contact to establish a second serially related arc, a substantially enclosed dashpot associated with the intermediate contact to control the latter's opening movement, and means rendering the dashpot ineffective during the initial portion of the opening operation.

7. In a circuit interrupter, a relatively stationary contact, an intermediate contact separable from the stationary contact to establish arcing, a movable contact separable from the intermediate contact to establish arcing, a substantially

enclosed dashpot isolated from the arcing pressure associated with the intermediate contact to regulate the opening movement thereof, and fluid regulating means for determining the time of actuation of the dashpot.

8. A circuit interrupter including an arc extinguishing unit submerged in liquid, a relatively stationary contact, an intermediate contact cooperable with the relatively stationary contact to establish an arc, a movable contact separable from the intermediate contact to establish a second serially related arc, a piston secured to and movable with the intermediate contact, an operating cylinder within which the piston moves, and means venting the forward side of the piston to the region exteriorly of the unit.

9. A circuit interrupter of the liquid-break type including an arc extinguishing unit submerged in the liquid, a relatively stationary contact, an intermediate contact cooperable with the relatively stationary contact to establish a pressure-generating arc, an enclosed dashpot protected from the arcing pressure associated with the intermediate contact to delay the opening movement of the latter, a movable contact separable from the intermediate contact to establish an interrupting arc, and means venting the dashpot to the region exteriorly of the unit.
